UNITED STATES PATENT OFFICE.

MICHAEL MILEY, OF SHEFFIELD TOWNSHIP, WARREN COUNTY, PENNSYLVANIA.

HAND-GRIP FOR SCYTHES.

1,042,708.

Specification of Letters Patent. Patented Oct. 29, 1912.

Application filed September 25, 1911. Serial No. 651,155.

To all whom it may concern:

Be it known that I, MICHAEL MILEY, a citizen of the United States, residing in Sheffield township, in the county of Warren, 5 State of Pennsylvania, have invented certain new and useful Improvements in Hand-Grips for Scythes; and I do hereby declare the following to be a full, clear, and exact description of the invention, such as will 10 enable others skilled in the art to which it appertains to make and use the same.

This invention relates to an improvement in hand grips for scythes of that type adapted to be readily attached to or detached from the usual scythe handles as 15 occasion may require.

The principal object of the invention is to provide a detachable hand grip of the character described, which is composed of a 20 minimum number of parts, is therefore simple in construction and is cheap to manufacture.

With these and other objects in view, the invention consists in the construction and 25 novel combination of parts hereinafter fully described, illustrated in the accompanying drawings, and pointed out in the claim here-to appended; it being understood that various changes in the form, proportion, size 30 and minor details of construction within the scope of the claim, may be resorted to without departing from the spirit or sacrificing any of the advantages of the invention.

35 In the drawing: Figure 1 is a detail elevation showing a scythe handle provided with a hand grip constructed in accordance with my invention, Fig. 2 is a top plan view of such a grip, the scythe handle being 40 shown in section, Fig. 3 is a longitudinal sectional view through the handle and grip, Fig. 4 is a plan view of the eye-bolt, Fig. 5 is a front view of the bushing.

Like reference numerals designate corre- 45 sponding parts in all the figures of the drawing.

Referring to the drawing, 5 designates the usual scythe handle and around this handle is disposed an eye 6 of an eye-bolt 7. This 50 bolt is formed with a reduced end 8, which is formed at its end with left hand threads

9. The bolt intermediate the eye and the reduced portion 8 is formed with right hand threads 10.

My invention further comprises a bushing 55 11, which is formed of metal and comprises a longitudinal bore 12 of a diameter slightly larger than the bolt 7 to permit the same to be freely slid therealong. The bushing further comprises a head 13 and a reduced 60 tapering portion 14. Projecting from the head 13 is a peripheral flange 15 forming a consequent groove 16, said flange projecting over and being in spaced relation to the reduced portion 14 of said head. Formed in 65 the face of the head 13 opposite the reduced portion 14 are diametrically opposed recesses 17—17 adapted to engage the eye 6 on either side of the bolt 7. The head on either side of the recesses 17 is concaved, as 70 at 18, to snugly fit the handle 5.

Associated with the right handed threads 10 of the bolt 7 is a nut 19, said nut engaging the smaller end of the reduced portion 14 to clamp the eye 6 and the head 13 firmly 75 to the handle.

The invention further comprises a wooden sleeve 20, which is formed with a bore 21 and a counterbore 22 adapted to respectively receive the reduced end 8 and the reduced 80 portion 14 of the bushing 13. The inner end of the sleeve is recessed, as at 23, to receive the flange 15 of the bushing. Formed in the outer end of the sleeve is an opening 24 of a shape to receive and prevent the rotation of a nut 25, which is threaded upon the left hand threads 9 of the reduced portion 8 of said eye-bolt. 85

From the foregoing, it will be observed that after the bolt 7, bushing 11 and nut 19 90 have been secured to the handle 5, as above noted, the sleeve 20 carrying the nut 25 is rotated toward the left until the said sleeve is firmly secured in place. It will be observed that by reason of the left hand 95 threads 9 any tendency of the sleeve 20 to become loosened during the operation of the scythe is prevented.

What is claimed is:

A hand grip for scythes comprising in 100 combination, a threaded bolt having a handle-receiving eye formed at one end, a

bushing slidably mounted on the bolt, said bushing including a head having its face formed with a pair of diametrically opposed pairs of recesses, the recesses of one pair being disposed at right angles to the other pair for respectively receiving the handle and eye, and a nut engageable with the bolt and bearing against the bushing for

drawing said eye and bushing against the handle.

In testimony whereof, I affix my signature, in presence of two witnesses.

MICHAEL MILEY.
